SNOW BLOWER APPARATUS

Richard G. Simmons, 3009 George St., Franklin Park, Ill.
Filed Feb. 27, 1961, Ser. No. 91,717
1 Claim. (Cl. 239—590)

My invention relates to snow blower apparatus, and more particularly, to blower apparatus that is especially adapted for removing snow from railroad track, though it is well suited for numerous other snow removal uses as well.

While the removal of snow and ice is an operation that brings no additional income to the railroads, it is a necessary maintenance problem for many railroads and presents difficulties that must be met each year to insure reasonably efficient operation during inclement weather.

The annual reoccurrence of the snow removal problem and continual rising costs of labor over the years have resulted in the development of many types of machines and devices for facilitating this operation. Conventional equipment available includes complex snow removal and melting plants, special plow carrying car units, accessories for spreaders, cranes and such off-track equipment as bulldozers, tractors and scrapers, loader and automobile trucks, as well as the use of pneumatic and electric tie tamping equipment for removing ice, and of weed burners for lighter snow falls.

Nevertheless, experience has shown that conventional equipment leaves much to be desired from the standpoint of reliable, efficient, economical operation, due to the complexity of the equipment and the need for skilled labor to operate same, the variable and generally unfavorable conditions under which such equipment must be operated, and the special snow removal efforts that must be met in connection with track switches, cross overs, and the like.

A principal object of this invention is to provide a snow removal apparatus that is not only reliable and economical to operate under a wide variety of operating conditions, but which also effects removal of, when necessary, even hard packed snow and ice.

Still another important object of the invention is to provide a simplified snow blower arrangement that may be applied to any convenient or existing wheeled frame for operation in combating the snow hazard.

A further important object of the invention is to provide a snow blower apparatus and method that is particularly adapted for use in railroad yards.

Other objects of the invention are to provide snow blower apparatus of the air blower type including a high capacity air source, to provide improved nozzles for concentrating the air flow where it is needed, to provide a snow ripper arrangement for breaking up hard snow and ice, to provide a snow blower arrangement that permits the use of standard wheeled frames for conveying same, and to provide a snow blower apparatus that is economical of manufacture, convenient to use and install, and efficient and reliable in operation.

Other objects, uses and advantages will be obvious or become apparent from a consideration of the following detailed description, when considered together with the accompanying drawings.

In the drawings:

FIGURE 1 is a side elevational view illustrating one embodiment of the invention as applied to railroad equipment;

FIGURE 2 is a plan view of the blower apparatus shown in FIGURE 1;

FIGURE 2a is a fragmental perspective view of a snow ripper nozzle in accordance with this invention;

FIGURE 3 is an elevational view of the blower duct

2

and nozzle structure shown in FIGURE 1, but on a somewhat enlarged scale;

FIGURE 4 is a cross-sectional view substantially along line 4—4 of FIGURE 2;

FIGURE 5 is a cross-sectional view substantially along line 5—5 of FIGURE 4;

FIGURES 6 and 7 are a side elevational view and plan view, respectively, of a modified form of blower apparatus;

FIGURES 8 and 9 are a side elevational view and a plan view, respectively, of still a further modified form of the blower apparatus;

FIGURE 10 is a plan view of the blower nozzle of the form shown in FIGURES 8 and 9; and

FIGURE 11 is an end view of the nozzle shown in FIGURE 10, taken substantially along line 11—11.

General Description

Referring now to FIGURES 1 and 2, reference numeral 10 generally indicates one embodiment of my invention applied to a more or less conventional railroad push car 12 that rides on track 14 applied in the usual manner to ties 16, which in turn rest on the customary ballast (not shown).

In the form of FIGURES 1 and 2, the car 12 is moved along the rails 15 of track 14 by a conventional driving push car 18 that is driven in any conventional and customary manner.

The apparatus 10 generally comprises a blower device 20 mounted in any suitable manner on a bed or platform 22 that may be carried by car 12 and connected to ducting 24 that includes a funnel member 26 and a nozzle member 28 that terminates in an outlet opening 30 which is generally oval shaped in the form of FIGURES 1 and 2.

In the embodiment of FIGURES 1 and 2, the nozzle member 28 is swivelly connected to the funnel member 24 by an appropriate type of swivel connection at the joint 32 and the nozzle member may be moved from side to side from the dashed line positions of FIGURE 2 by the operator rotating actuating shaft 36 by using hand wheel 38, which turns the nozzle member 28 with respect to the funnel member through a cable 40, both ends of which are fixed to a spindle 42 that is keyed to shaft 36, and the center of which is fixed to the nozzle member 28 in any suitable manner, as by welding at 43.

The blower device 20 is of the general type illustrated in FIGURES 4 and 5, and is actuated by an appropriate power unit 44 through an appropriate clutch 46 and couplings 48. A guard 50 in the form of a relatively large mesh screening is applied over the intake side of the blower device 20.

The blower 10 also includes snow ripper devices 60 that are applied on either side of the nozzle member 28. The ripper devices 60 each comprise relatively small diameter piping conduits 62 secured to the car 12 in any suitable manner, as by appropriate clamps 64 and terminating in bifurcated nozzles 66 that define nozzle elements 68 positioned on either side of a track rail 15. The conduit 62 may be connected by flexible conduits 70 to an appropriate form of air compressor 72 carried by the push car 18. However, any suitable source of air may be employed to supply nozzles 66 with the air flow desired, and it is contemplated that the car 12 may be arranged to carry an air compressor for this purpose.

In accordance with this invention, the blower device 20 and the nozzle member 28 are arranged to apply in a concentrated manner as large a volume flow of air as reasonably possible to the track bed between and selectively against the individual track rails 15. In a specific form of the apparatus shown in FIGURE 1, the blower device 20 is a 29 inch vane-axial blower made by the Hartzell Propeller Fan Company of Piqua, Ohio (which has a

2,400 r.p.m. 17,000 cubic foot per minute capacity rating), while the nozzle member 28 is a tube that is round in cross-sectional configuration and terminates in a nozzle opening that is on the order of one and a half square foot in area.

The apparatus 10 is particularly adapted for use in railroad yards. After a snowfall has commenced and it appears that snow removal will be required, apparatus 10 is moved onto the yard track and continuously operated over the yard track as long as the snowfall continues to accumulate or drift. This is done by employing the power actuated push car 18, or in any other suitable arrangement, to move the apparatus 10 in a forward direction (to the right of FIGURES 1 and 2) as required to free the track of snow and ice.

During operation of apparatus 10, motor 44 actuates blower device 20 to supply a large volume air flow to the nozzle member 28, from which it is emitted with a force comparable to 100 m.p.h. gale. The nozzle member 28 is angled somewhat as shown with respect to the track bed (approximately 45 degrees from the vertical in the illustrated embodiment of FIGURES 1 and 2) and as apparatus 10 is moved along the track, nozzle member 28 is moved back and forth between the dashed line position of FIGURE 2 to effect removal of snow that is accumulated on the track bed and rails.

Where weather conditions have resulted in the formation of hardened snow and ice across the track rails, the ripper devices 60 are actuated by supplying air under pressure to the conduiting 62. Conduiting 62 are relatively small in diameter (3/4 inch pipe in the illustrated embodiment) and the air which is supplied by a standard air compressor of suitable capacity, emits from nozzle elements 68 in the form of relatively fine air jet blasts on either side of the individual rails 15, which break up hardened snow and ice for removal by the nozzle 28. After such hardened snow and ice has been broken on either side of the individual rails 15, the large volume continuous air blast from the nozzle member 28 will readily blow the refuse to one side of the track bed.

It will be obvious, of course, that apparatus 10 is fully operative on any trackage, but the concentration of traffic and the consequent necessary track equipment in yards makes yard use of apparatus 10, as well as the other modifications illustrated, of particular significance.

In the embodiment of FIGURE 1, a flow directing baffle 76 is applied across the rear of the nozzle open end 31 to prevent backflow of the air leaving nozzle member 28 and accentuate the forward thrust of the air blast leaving the blower apparatus. Baffle 76 also defines part of opening 30 in this embodiment of the invention.

In the embodiment 10a of FIGURES 6 and 7, the nozzle member 28a is bifurcated to define laterally directed tubes 80 that terminate in nozzle elements 82, the outlet openings 30a of which are positioned above the track rails 15 approximately as indicated in these two figures. The nozzle elements 82 have approximately the same angulation with respect to the track bed as the embodiment of FIGURES 1 and 2, and define nozzle openings 30a that together have a composite effective area on the order of one and one-half square feet.

Nozzle member 28a is connected to funnel member 26 by an elbow structure 84 and an extension structure 86, but, of course, this intermediate connecting arrangement may be of any suitable character.

The form of FIGURES 6 and 7 also illustrates the modified snow ripper arrangement 60a wherein a conduit 90 connects the nozzles 66 on either side of the nozzle member 28a, and nozzle elements 68 are applied across the entire track bed between rails 15, somewhat as indicated in FIGURE 7.

The embodiment of FIGURES 6 and 7 is otherwise substantially the same as that of FIGURES 1 and 2, as indicated by corresponding identical reference numerals, though in this embodiment, the nozzle member 28a is fixed with respect to the funnel member 28, and con-

sequently the shaft 36 of FIGURES 1 and 2 and its appurtenant parts are eliminated.

The embodiment of FIGURES 6 and 7 is operated in substantially the same way as that of FIGURES 1 and 2 except that nozzle member 28a is not rotated. This form of the invention is particularly adapted for clearing snow from under switch points, where the ballast level is usually below the tops of the ties.

In the embodiment of FIGURES 8-11, the nozzle member 28b is formed to terminate in an elongate narrow outlet opening 30b, which is made of sufficient length to extend over and between both track rails 15, as indicated in FIGURE 1, while retaining an orifice area of one and one-half square feet. Nozzle member 28b is connected 15 to funnel member 24 by an appropriate elbow member 10.

As shown in FIGURES 10 and 11, the nozzle member 28b is provided with air flow directing vanes or baffles 102, 104 and 106, which are essentially planar plates fixed 20 between the sides 108 and 110 of the nozzle member. Preferably, supplemental flow directing vanes or baffles 112 are secured in place adjacent the baffles or vanes 102 and 106 in approximately the positions indicated in FIGURE 10 for the purpose of better insuring the sidewise blowing action of the air blast emitting from nozzle member 28b. As indicated, the vanes or baffles 112 should be approximately parallel to the respective sides 114 of the nozzle member 28b.

The apparatus 10b is otherwise essentially the same as 30 that shown in FIGURES 1 and 2, as indicated by corresponding identical reference numerals.

Specific Description

The specific form of blower device 20 employed in the 35 illustrated embodiments of the invention is best shown in FIGURES 4 and 5.

It will there be seen that the blower device 20 generally comprises an annular outer housing member 120 fixed to an inner annular housing member 122, as by welding 40 appropriate spacer baffles 124 to both of these members; baffles 124 are preferably symmetrically arranged about the blower device 20 and may be of any suitable number commensurate with the strength requirements to be satisfied. The 29 inch blower size previously mentioned corresponds to the internal diameter of housing member 120.

The inner housing member 122 has fixed within same spaced support structures 126 for the respective pillow block bearing units 128 that are employed to journal blower shaft 130. Blower shaft 130 has keyed thereto a 50 rotor 132 provided with spaced vanes or blades 134 angled as required to create a high volume air flow through the annular chamber 136, that is defined by the housing members 120 and 122, in the direction of arrows 137, when the shaft and rotor are rotated in the direction of the arrow 129 of FIGURE 5. An appropriate cover 138 is fixed 55 over the rotor 132 in the illustrated embodiment of FIGURE 4.

It will be apparent that the bearing units 128 may be 60 of any suitable type, though they usually are of the ball bearing form for applications such as that illustrated. Likewise, the support structures may be of any convenient form, such as that diagrammatically illustrated in FIGURE 5 which contemplates plates 140 welded or otherwise secured in operative position with housing member 122 in association with brackets 141.

The motor 44, the clutch 46, the couplings 48, and other devices essential for transmitting the motive power of motor 44 to shaft 130 may be of any conventional and suitable type. In the present instance, motor 44 is a 35 horsepower gasoline engine operating at 2,400 r.p.m. under load conditions. Clutch 46 is operated by using handle 150 to stop and start blower device 20.

The guard 50 is formed in any suitable manner from a large mesh screening material that preferably has mesh 70 openings defining an opening area on the order of that

defined by one and one-half inch square mesh openings. The shafting 151 for driving shaft 130 extends through the cover 50 in any suitable manner. Cover 50 may be secured in place in any suitable manner.

The ducting 24 including funnel member 26 and nozzle member 28 may be formed from any suitable materials, though 12 gauge sheet metal is considered appropriate for the embodiment of FIGURES 1 and 2. Member 26 is formed with connecting flanges 152 for cooperation with the adjacent flange 154 of the blower device 20 and the adjacent flange 156 of the nozzle member 28, for purposes of appropriately securing these elements together. As already indicated, the swivel connection between nozzle member 28 and funnel member 26 may be of any suitable type, while funnel member 26 may be secured to housing 120 by bolts or welding or in any suitable manner.

The ripper nozzles 66 and their associated conduit may assume any appropriate type of piping, and may be supported or braced in any suitable manner, though for $\frac{3}{4}$ inch piping, conduit 62 should be supplied with air at a rate on the order of 250 cubic feet per minute. However, the arrangement should be such that the nozzles 66 extend forwardly of the nozzle member 28, somewhat as indicated in FIGURES 1 and 2, so that the snow and ice broken up by them will be swept away by the air blast from nozzle 28 as the apparatus 10 moves in a forward direction.

Nozzle elements 68 (see FIGURE 2a) preferably comprise short $\frac{3}{4}$ inch pipe lengths with their tips 159 flattened to define outlet orifices 161 on the order of $\frac{1}{16}$ of an inch in width. Elements 68 should be secured in place so that the wide dimension of the respective orifices lies in a plane that is parallel to the direction of movement. Thus, nozzles 68 will emit flat high velocity jets that provide a knife-like cutting action on either side of the respective track rails as the blower apparatus moves along the track.

The shaft 36 for actuating nozzle member 28 may be secured in place in any suitable manner, as by being rotatably applied to the spaced brace members 160 that are in turn welded to the respective members 26 and 120.

The platform 22 that is carried by car 12 is provided with appropriate flooring where indicated at 162 to accommodate the operator. In the illustrated embodiments, flooring 162 as well as motor 44 and blower device 20 are mounted in any suitable manner on bed 22, and bed 22 takes the form of a separable pallet 163 that is removably applied to car 12. Bed 22 as well as car 12 may take any suitable form; and, of course, car 12 need not be of the railroad type unless the snow removal purposes of the apparatus are to be confined by users to railroad track.

In the specific embodiments illustrated, car 12 takes the form of a standard push car frame 166 including the customary railroad type flanged wheels 168 that are journaled in frame 166 in any suitable manner and ride on rails 15. Bed 22 comprises spaced channel beams 167 fixed together in any suitable manner and carrying suitable angle brackets 169 adapted to be fixed to car 12 by appropriate bolts 169a or the like. Suitable eyes 165 or the like may be secured to the motor 44 and housing 120, or elsewhere, for purposes of crane lifting pallet 163 between vehicles that are to support same. I contemplate also that pallet 163 may be secured in place in some manner that permits adjustment of the nozzle (28-26b), both vertically and with regard to its angulation from the vertical. This may take the form of adjustably securing brackets 169 to beams 167 so that the bed 22 may be shimmed to the desired adjustment, or shims, as desired, may be applied under brackets 169 or beams 167 before bolts 169a are applied.

In the embodiment of FIGURES 8-11, the nozzle member 28b and elbow 100 are formed from 12 gauge sheet metal, though any other suitable material may be employed. Flanges 180 are provided on these parts for securing the various members together by appropriate bolts 182.

In a preferred form of the embodiment of FIGURES 8-11, the nozzle opening 30b is six feet in length and three inches in width, making the length of the opening 30b approximately 24 times its width and adequate to cover both rails of U.S. standard gauge track (U.S. standard gauge is $56\frac{1}{2}$ inches). Using the blower and motor units indicated, the dimensioning of nozzle opening 30b permits an air flow on the order of 10,500 cubic foot per minute to sweep the track across the length of the ties; the vanes 112 insure that the air flow from nozzle 28b acts the full length of the ties, which is normally on the order of eight feet. Nozzle 28b should be angled somewhat with respect to the track, an angulation on the order of 10 degrees from the vertical (assuming a level or horizontal track bed) being preferred. In other words, the air blast from nozzle 28b should be applied against the track at an angle that is at least on the order of 80 degrees with respect to the track.

I have found that there is a critical relationship between the size of the nozzle discharge opening and the volume flow of air through same that must be observed to obtain the most effective blowing action for snow removal purposes, and this is complied with by providing an effective nozzle discharge opening area on the order of one and one-half square feet and providing for a discharge flow rate on the order of 10,000 cubic feet per minute. This relationship is observed in all the illustrated embodiments and constitutes an important aspect of the invention. The shape of the nozzle discharge opening is immaterial as far as the relationship is concerned, and it is also immaterial what type of air actuator is used, though it should have a capacity on the order of that mentioned concerning blower device 20.

Distinguishing Characteristics of the Invention

It will therefore be seen that I have provided a blower apparatus arrangement contemplating the use of a high capacity source of air flow fed to a large bore ducting arrangement terminating in a nozzle arrangement having a reduced but still comparatively large area outlet opening for rapid discharge of a continuous large volume fast moving blast of air. The nozzle arrangement is such that deflection of the air blast discharge laterally of the blower apparatus is insured to blow accumulated snow to either side of a track. This lateral deflection is provided in the embodiment of FIGURES 1 and 2 by the swivel mounting of the nozzle member, while in the embodiment of FIGURES 6 and 7, and 8-11 it is insured by the shape of the specific nozzle members there illustrated.

An important feature of the illustrated embodiments is that the blower 20 in effect packs the respective nozzles 28-28b with air so that the additional air compression achieved by so doing, together with the outline of openings 30-30b provide a marked increase in the air blast effect on the snow due to the expanding of the air as it leaves the nozzle. The nozzle opening area and volume rate of air flow therefrom that have been indicated are considered optimums for standard U.S. railroad dimensions.

Operable in conjunction with the large volume nozzle discharge are the snow and ice ripper devices, which essentially provide relatively fine high powered flat air jets that operate forwardly of the blower apparatus to blow traces or slits in hard snow and ice and thereby break it up so that it can be blown to one side by the large volume nozzle structure.

While my invention has been disclosed in association with railroad car equipment, it will be immediately apparent that the basic principles may be applied to the removal of snow from air fields, streets or any other flat area where snow accumulation is to be avoided. The removable pallet arrangement in which the blower, ducting, nozzle and motor components are incorporated makes the apparatus unusually versatile and readily transferable between appropriate vehicles or other supporting structures.

The various forms of the invention may be used for track cleaning purposes other than snow removal, such as the removal of engine sand from switch leads and yard track, and for blowing ballast away from ties when performing track raising operations, so as to permit operation of tie adzing machines.

The foregoing description and the drawings are given merely to explain and illustrate my invention and the invention is not to be limited thereto, except insofar as the appended claims are so limited, since those skilled in the art who have my disclosure before them will be able to make modifications and variations therein without departing from the scope of the invention.

I claim:

A nozzle for railroad track snow blower apparatus, 15 said nozzle comprising a tubular structure formed to define a rounded inlet opening at one end and an elongate outlet opening at the other end thereof having an effective discharge area that is at least on the order of one and one-half square feet, with the long dimension of 20 said outlet opening being on the order of twenty-four times as long as the narrow dimension thereof, said outlet opening thereby being proportioned to permit an air flow therethrough at a rate on the order of 10,000 cubic feet per minute, said outlet opening being proportioned to 25 extend over and between the rails of a track, when the nozzle is positioned above a track with said outlet extending transversely thereof, said inlet opening being proportioned to admit air flow into said nozzle at said rate, said tubular structure including baffle means for 30 symmetrically subdividing the bore of said tubular structure into passages extending longitudinally of said tubular structure, said baffle means comprising spaced imperforate planar members disposed in planes that are perpendicu-

lar to the plane that includes both the axis of said bore and the longitudinal axis of said outlet opening and that diverge outwardly of said outlet opening, and a pair of supplemental flow deflecting baffles secured within said tubular structure adjacent said outlet opening, said supplemental baffles being disposed on either side of said bore axis adjacent the ends of said outlet opening longitudinal axis and being respectively secured to an adjacent planar member of said planar members and projecting toward said opening, said supplemental baffles extending substantially parallel to the respective sides of said tubular structure that they are adjacent to.
